Primary Examiner — Karen S Acker*Assistant Examiner* — Clare Ann Gannon(74) Attorney, Agent, or Firm — Oliff PLC(57) CLAIM

The ornamental design for a non-woven textile, as shown and described.

DESCRIPTION

The sole drawing is a plan view of the non-woven textile. The broken lines show portions of the non-woven textile that are not included in the claim. The broken lines and the area surrounding the solid lines form no part of the claimed design. The non-woven textile is flat.
